UNITED STATES PATENT OFFICE.

NILS H. ANDERSON, OF MIDDLETOWN, CONNECTICUT, ASSIGNOR TO THE NOISELESS TYPEWRITER COMPANY, OF MIDDLETOWN, CONNECTICUT, A CORPORATION OF CONNECTICUT.

TYPE-WRITING MACHINE.

1,163,936.

Specification of Letters Patent. Patented Dec. 14, 1915.

Application filed May 14, 1910. Serial No. 561,416.

To all whom it may concern:

Be it known that I, NILS H. ANDERSON, a citizen of the United States, residing at Middletown, in the county of Middlesex and State of Connecticut, have invented certain new and useful Improvements in Type-Writing Machines, of which the following is a full, clear, and exact description, such as will enable others skilled in the art to which it appertains to make and use the same.

This invention relates to typewriting machines, and with regard to the more specific features thereof, to mechanism adapted to positively control the movement of the bearings between the carriage and the part along which the carriage is adapted to travel.

One of the objects of the present invention is to provide a simple and practical construction of the above nature which will be positive in operation.

Another object is to provide mechanism of the above character which will be efficient in use and of compact arrangement.

Another object is to provide a construction of the above nature which will be cheap to manufacture and easy to install.

A further object is to provide an improved self-contained ball retainer that may be readily installed or removed from the machine.

Other objects will be in part obvious and in part pointed out hereinafter.

The invention accordingly consists in the features of construction, combination of elements and arrangement of parts which will be exemplified in the construction herein-after set forth, and the scope of the application of which will be indicated in the following claim.

40 In the accompanying drawing, wherein is shown one of various possible embodiments of this invention,

Figure 1 is an elevation, partly in section, of a portion of a typewriting machine sufficient to illustrate one application of the present invention; Fig. 2 is an end elevation, partly in section, showing the platen carriage and shift rail; Fig. 3 is a plan view of the blank from which the ball retainer is formed; Figs. 4, 5 and 6 are detail views at right angles to each other of a part of the retainer.

Similar reference characters refer to simi-

lar parts throughout the several views of the drawing.

Referring to this drawing in detail, 1 represents a carriage which may be of any well-known construction, but in the embodiment herein shown is of the style used on the noiseless typewriting machine. This carriage is provided with upper and lower guide rails 2 and 3, respectively, spaced apart and coacting with an intermediate shift rail 4 supporting the carriage and along which it travels.

The upper and lower guide rails and the shift rail 4 are provided, along their adjacent surfaces, with V-shaped runways, in which are mounted a plurality of anti-friction devices, preferably steel balls 5. These balls are held in relative position by means of a retainer 6 extending longitudinally parallel with the guideways in the carriage and shift rail, and containing openings 8, through which the balls extend, whereby they are retained in proper relative position.

While the retainer may be of any suitable material and shape, it is preferably made from a blank such as shown in Fig. 3, stamped from sheet metal. The blank is generally rectangular with enlarged corner portions 7 connected by longitudinal and transverse members, defining an open central portion, where the metal has been removed in order to lighten the retainer. Extending from one of the longitudinal members at its central portion is a tongue 12, in which a pinion is to be mounted, as herein-after referred to. To complete the retainer it is bent so that the corner portions 7 and the longitudinal members extend in the same direction and at an angle, preferably a right angle, to the body portion, with the tongue 12 projecting downward, as shown in end elevation in Fig. 3. The transverse members of the retainer are bent intermediate their ends so that the lower portions thereof are out of the vertical plane of the upper portions, the purpose of which will appear hereinafter.

Diametrically opposite in the wall of each hole 8 is a short slit or opening 9 parallel to the length of the retainer, for receiving a flat perforated keeper 10, preferably punched out from sheet metal, which receives and surrounds one of the balls 5.

Each end of the keeper is split or forked, as at 11, (see Figs. 4 and 5) whereby after it has been inserted in the retainer and perpendicular to the plane thereof at that point, 5 the prongs of each forked end may be bent in opposite directions to hold the keeper in place; and as the runways in the guide and shift rails are of V-shape in cross section, the retainer may reciprocate freely without 10 either the retainer or keeper engaging the same. In this manner the balls are caged and held in relative position and may be removed or installed easily and quickly as an integer. Moreover, the keeper 10 provides a 15 means whereby the balls may be easily removed from the retainer when desired, by an obvious manipulation of the split ends.

The tongue 12, depending from the central part of the upper side of the retainer, 20 carries a bearing sleeve 13 (see Fig. 6) in which is mounted a pinion 14 (see Fig. 1) meshing at one side with a rack 15 secured to the shift rail 4, and at its opposite side with a second rack 16 held between the 25 guide rail 3 and the carriage 1, as shown in Fig. 2, the upper part of the rack being bent rearward for reasons hereinafter set forth. The upper guide rail 2 of the carriage is provided with a depending portion 30 17 normally out of contact with the upper part of the retainer, while the lower part of the retainer, as before explained, is bent forward, as shown at 18, so that the lower portion thereof lies forward of the bent 35 rack 16. It will thus be seen that as the carriage is moved along in a letter-spacing direction, the pinion 14 meshing with the fixed rack 15 on the shift rail and the movable rack 16 on the carriage will carry the 40 retainer 6 along in the same direction as the movement of the carriage, but at one-half the speed thereof. In this way a gradual slipping or creeping of the balls toward one end of the carriage is prevented, 45 due to the variable movement, as when tabulating, and the difference in relative rate of speed of the carriage in its backward and forward movement. The creeping of the balls would eventually bind and 50 retard the movement of the carriage near the end of its path of travel.

By the use of the construction herein set

forth the bearings are maintained in proper relation to the carriage throughout its movements.

55

It will thus be noted that this invention provides for a simple, practical and self-contained device having few parts compactly arranged, which will be cheap to manufacture and easy to assemble, attaining, among others, the objects and advantages above set forth.

60

As many changes could be made in the above construction and many apparently widely different embodiments of this invention could be made without departing from the scope thereof, it is intended that all matter contained in the above description or shown in the accompanying drawings shall be interpreted as illustrative and 65 not in a limiting sense.

70

It is also to be understood that the language used in the following claim is intended to cover all of the generic and specific features of the invention herein described and all statements of the scope of the invention, which, as a matter of language, might be said to fall therebetween.

75

Having described my invention, what I claim as new and desire to secure by Letters Patent is:

80

In a device of the character described, in combination, a carriage having upper and lower guide rails, a shift rail therebetween along which the carriage is adapted to 85 travel, bearings between the shift rail and the guide rails, a rack mounted on said shift rail, a second rack between said lower guide rail and the body of the carriage, a retainer for said bearings, and a pinion 90 carried by said retainer adapted to mesh with both of said racks, whereby the movement of the bearings is positively controlled, the upper guide rail of said carriage having a depending portion adapted 95 to prevent a lateral movement of said retainer.

In testimony whereof I affix my signature, in the presence of two witnesses.

NILS H. ANDERSON.
